[57] ABSTRACT

A compact fluid powered actuator is constructed from a flexible tube assembled over a rigid core. The actuator includes an expandable chamber formed between the tube and the core. The chamber is bounded by naturally efficient and lowly stressed seals at the ends of the tube which tightly match the periphery of the core. This construction lends itself to mass production methods wherein a long core is assembled with a long tube enabling a plurality of actuators to be manufactured simultaneously.

METHOD OF MAKING A COMPACT FLUID ACTUATOR

CROSS REFERENCE TO CO-PENDING APPLICATION

This application is a division of my co-pending application, Ser. No. 98,775, filed Dec. 16, 1970, now U.S. Pat. No. 3,703,853.

BACKGROUND OF THE INVENTION

Bellows, pistons and diaphragms have long been employed as expansible chamber actuators for converting pneumatic or hydraulic energy into an output force. A typical limitation on the use of actuators has been the cost and complexity of overcoming, or of living with, the problems of fluid sealing and in the case of a bellows or diaphragm, fracture of a flexible member.

Of these three traditional actuators, the bellows provide the greatest simplicity since it can be manufactured somewhat as a single member. The traditional bellows includes a plurality of so-called accordion pleats which enable a significant output stroke. The apex of each pleat has a small radius bend which is subject to failure upon repeated stressing. The bellows device, while mechanically simple due to its potential one piece construction, is rather complex from a manufacturing viewpoint particularly where small size bellows are concerned. In small size bellows the uniformity of wall thickness will determine the reliability of the bellows over a long period of time. Those skilled in the art familiar with the techniques for molding thin complex walls of flexible material and maintaining uniform wall thickness can recognize the limitations of the bellows actuator.

My invention employs the readily manufacturable shapes of a rigid cylinder and a flexible tube to minimize the sealing and flexure problem of an expansible chamber in a simple and highly effective manner. A tube press-fit over a cylinder of substantially equal periphery forms a natural seal which can be easily supplemented by a heat bond if desired. The reaction and support functions necessary to the actuator are compactly provided by the internal rigid core which lends itself to a simple snap-in frame mounting like that common to some fuses of similar shape. While the construction of the tube can be varied to some extent, I prefer to employ a relatively non-elastic material that is pre-formed into a bulge defining the expansible chamber. Actuation of the device thus involves only flexural deformation rather than any significant amount of stretching. Due to the surrounding relationship of the tube with the cylindrical core, it is possible to restrict flexure to relatively large radii of curvature and thereby minimize the tendency for local failure that limits the potential success of a bellows type device.

While the actuator that I have invented has the capabilities indicated above which by themselves make it a desirable and highly effective device, it should be apparent that the simple shapes of tubes and cylinders can be manufactured to relatively close tolerances. Uniform wall thickness of a tube is relatively easy to obtain. Such uniformity is required to minimize stress concentrations that could cause localized failure. My actuator also lends itself to large quantity manufacture to minimize its basic cost. The fundamental shapes of a cylinder and a tube enable simultaneous construction of a plurality of expansible chambers on a long rod sur-

rounded by a long tube. These devices can later be severed into a plurality.

These and other concepts, features, and advantages of my fluid actuator and the method of making it will be apparent to those skilled in the art from reading and understanding the following more specific illustrative embodiment of my invention wherein reference is made to the accompanying drawings, of which:

FIG. 1 is a perspective view of a fluid actuator constructed in accordance with my invention;

FIG. 2 is a longitudinal cross-sectional view of the actuator shown in FIG. 1 and taken along lines II — II of FIG. 1;

FIG. 3 is a lateral or end cross-sectional view of the actuator shown in FIG. 1 taken along lines III — III thereof;

FIG. 4 is a perspective view of the cylindrical core component of the actuator shown in FIG. 1;

FIG. 5 is a perspective view of the tubular component of the actuator shown in FIG. 1;

FIG. 6 is a somewhat schematic view showing a method of making the cylindrical core component of an actuator in accordance with my invention;

FIG. 7 is a schematic view showing a preferred method of forming the tubular component after assembly with the core component in accordance with my invention and

FIG. 8 is a schematic manufacturing view showing the separation of a plurality of simultaneously formed devices into individual devices.

Referring now more specifically to the drawings, in FIGS. 1, 2, and 3 there is shown a compact fluid powered actuator or device 10 comprising a substantially rigid elongated core member 20 that is best seen in FIG. 4. Core member 20 is surrounded by a flexible relatively non-elastic, fluid impervious, tubular membrane or tube 30 that is best seen in FIG. 5. The tube 30 includes a bulge portion 31 that overlies an intermediate positioned recessed section 21 of the core member 20 to form an inflatable or expansible chamber 32. Fluid for inflating chamber 32 is supplied through a suitable conduit 11 within the core member 20. The fluid is transmitted through an inlet 22 and a longitudinal bore 23 to an elongated channel portion 23a where it is applied internally to the tube 30 to cause inflation of the chamber 32. Due to the inelastic character of tube 30, bulge portion 31 defines a fixed maximum volume for chamber 32 when inflated as shown in broken lines in FIG. 2.

An output member 40 is movably supported by a pivot axis or shaft 41 connected to a mounting bracket 42. As shown in broken lines in FIG. 2, output member 40 is driven upwardly upon inflation of the chamber 32. The mounting bracket 42 is secured to a frame part 43 by a screw 44 and includes a pair of spaced spring clip portions 45 for securely receiving the ends of the core member 20. It will be seen that upwardly turned portions 46 of the spring clip portions 45 will resiliently removably receive the core 20 in a manner similar to an elongated fuse mounting. Obviously other mounting devices can be employed with equal facility.

The details of the core member 20 are better shown in FIG. 4. The core member 20 is essentially of oblong cylindrical lateral cross-sectional or peripheral configuration. This cross-section, which is substantially uniform at opposite end sections 24, provides a flattened configuration having opposed primary surface portions

25 that provide a relatively large area compared to the side or secondary surface portions 26. The recessed section 21 has a longitudinal extent 27 that is long relative to the width 28 of the core member 20 thereby providing a relatively large potential surface area to lie in projection with the bulge portion 31 of the tube 30.

The recessed section 21 also has a surface configuration 21a that is made substantially complementary to the shape of a force receiving portion 47 of the output member 40. As best seen in FIG. 2, the force receiving portion 47 thus snuggly fits against the bulge portion 31 of the tube 30 and rests against the complementary configured surface 21a (see FIG. 3) of the recessed portion 21 to define a stable end limit or rest position. Only a single layer of uncrimped membrane of the tube 30 lies between the force receiving portion 47 and the surface 21a, since as shown in FIG. 3, the excess material of the bulge portion 31 moves outwardly to the side where it does not interfere with the precise rest position of output member 40.

The core member 20 can be made of a variety of materials and by processes that include both molding and machining. If the core member 20 is made from stock material including the longitudinal bore 23 which extends throughout the entire length thereof, then a plug 23b must be provided to seal one end of the bore 23.

The tube 30, as shown in FIG. 5, has an internal periphery that is substantially equal to the external periphery of the core member end portions 24 to provide a tight fit therewith. It is preferable to employ a relatively non-elastic, but thermoplastic material in constructing the tube 30 to enable the molding of bulge 31 after the tube 30 has been mounted upon the core member 20. It will be recognized however that advantages remain even if an elastic membrane is employed without a pre-formed bulge 31.

The tube 30 is assembled with the core member 20 by moving the tube 30 along the longitudinal axis 29 of the core member 20 and is natural sealed therewith by the interference between the tube 30 and the end portions 24 of the core member 20. This natural seal can be supplemented by thermoplastic bonding at 33 through the use of a heated tool or an ultrasonic device. Having assembled an inflatable device comprising the tube 30 mounted on the core member 20, the actuator is constructed simply by plugging this device into the mounting bracket 42 shown in FIG. 1.

The fundamentally simple and compatable shapes of a cylindrical core member and a tubular membrane enable efficient mass production of these actuators. As shown in FIG. 6, an elongated rod of stock material 50 provided with a longitudinally extending bore 51 is machined by a cutting tool 60 to provide a plurality of spaced recesses 52 which are separated by unmodified sections 53 therebetween. Having manufactured a core member with a plurality of recessed sections 52 therein, a thermoplastic tubular membrane 54 is forced thereon with somewhat of a press fit. This elongated assembly then is placed in a mold 61 as shown in FIG. 7 containing a plurality of mold cavities each having a surface configuration 62 that defines the desired inflated shape of the bulge portion 31 (see FIGS. 2 and 5). Also the mold can contain heating devices 63 for bonding the tube 54 to the core sections 53. The tubular membrane 54 is heated prior to insertion in the mold to a temperature where it is thermoplastic. When

the elongated heated assembly is placed in the mold 61, the membrane 54 is stretched by inflation through either the application of pressure to the bore 51 or by drawing a vacuum in the mold cavities 62. The stressed membrane thus permanently stretches to a shape defined by the mold cavity surface 62 and when cooled will remain in this configuration. As shown in FIG. 8, the molded assembly is divided into individual fluid devices 55 by a cutter 64 and later can be finally processed to the specific configuration desired as shown in FIG. 1 for example.

Those skilled in the art will recognize that I have disclosed a uniquely simple but effective fluid actuator concept which can be embodied in a variety of materials and manufactured in a variety of ways. While a specific embodiment and a specific manufacturing method have been disclosed to enable those skilled in the art to understand and practice my invention, it is to be recognized that various modifications can be made without departing from the inventive concepts I have disclosed. Accordingly these concepts are to be limited only by the specific language of the appended claims.

I claim:

1. A method of making a fluid operable device comprising the steps of:

providing a substantially rigid elongated core member having a recessed section intermediate a pair of opposed end sections of equal lateral periphery and having a bore extending through one of said end sections and intersecting said recessed section, providing a fluid impervious, flexible tubular membrane having a length greater than said recessed section taken along the axis of elongation of said core member and at least portions thereof having an internal lateral periphery that is approximately equal to the lateral periphery of said end sections,

inserting said core member into said tubular membrane, and plastically deforming said tubular membrane in the region overlying said recessed section to form a bulge.

2. A method of making a fluid operable device as defined in claim 1 wherein said step of providing a core member comprises the steps of:

providing stock material having a uniform peripheral configuration, and removing material from an intermediate portion of said stock material to form said recessed section.

3. A method as defined in claim 2 wherein said stock material provided includes a longitudinal bore extending the length of said stock material and the method further comprises plugging said bore at one end thereof.

4. A method as defined in claim 1 wherein said deforming step comprises:

placing the assembled membrane and core member into a mold having a mold cavity surface portion in operative projection with that portion of said membrane that overlies the recessed section of said core member,

heating said membrane to a softening temperature, and

introducing fluid into the bore of said core member to stretch said membrane into contact with said mold cavity surface portion.

5. A method as defined in claim 1 comprising the further step of:

heat sealing said membrane to said core member where said membrane overlies said core member end sections.

6. A method of making a plurality of fluid operable devices comprising the steps of:

providing a substantially rigid elongated core member having a plurality of longitudinally spaced recessed sections formed in the external surface thereof and having a longitudinally extending bore formed therein to substantially the entire length of the core member,

providing an elongated, fluid impervious flexible tubular membrane having an internal lateral periphery that is approximately equal to the lateral periphery of said core member in the sections thereof between said recessed sections, inserting said core member into said membrane, sealing said membrane to said core member in those sections of said core member between said recessed sections thereof, and

severing said membrane and core member at intermediate points of said sections between said recessed sections to form a plurality of individual fluid operable devices.

5 7. A method of making a fluid operable device comprising the steps of:

providing a substantially rigid elongated core member having a recessed section intermediate a pair of opposed end sections of equal lateral periphery and having a bore extending through one of said end sections and intersecting said recessed section, surrounding about said core member, a fluid impervious, flexible tubular membrane having a length greater than said recessed section taken along the axis of elongation of said core member and at least portions thereof having an internal lateral periphery that is approximately equal to the lateral periphery of said end sections, and plastically deforming said membrane in the region overlying said recessed section to form a bulge.
